COMBUSTION CONTROL FOR HEATING SYSTEMS

Albert W. Holmes, Providence, R. I.

Application August 30, 1932, Serial No. 631,005

6 Claims. (CL 110—75)

My present invention relates to the heating art, and has particular reference to the control of combustion of hand fired stoves, furnaces, and boilers.

5 Careful study of the combustion of coal in the above has disclosed that approximately fourteen pounds of air must be supplied per pound of coal consumed, and that about one half must be supplied below the grate as primary air, and one half 10 in the combustion space above the fire as secondary air, to ensure complete combustion.

Complete combustion under usual operating conditions has been found to require an initial or primary combustion, and a subordinate or secondary combustion, the primary combustion occurring on the grate bars and in the fire bed, and the secondary combustion occurring in the combustion space above the fire bed. The primary combustion requires a sufficient supply of air under the grate bars, and a sufficient temperature to produce the desired combustion; this is obtained by controlling the flow of air into the ash pit, or under the grate bars, and regulating the rate of gasification of the coal in the fuel bed. The secondary combustion requires admission of 25 a sufficient supply of air to the combustion space, a thorough mixture of this air with the gases from the fuel bed, sufficient temperature to complete the combustion, sufficient space to permit the necessary expansion of the gases during the combustion process, and control of the outflow so as to 30 permit the combustion to be completed.

Efficient furnace operation thus requires accurate control of the primary air, the secondary air, and the speed of combustion, as the combustible gases must have sufficient time in the fire box for complete combustion. Moreover, the secondary air should be heated, and injected into the combustion space so as to spread over the fuel bed and thoroughly mix with the gases ascending from the fuel bed.

It is the principal object of my invention to control the supply of primary air, secondary air, and the speed of combustion so as to obtain maximum efficiency. Other objects of my invention are to preheat the secondary air and to inject the secondary air in many small streams over the fuel bed so as to thoroughly mix oxygen with the combustible gases and complete the combustion.

With the above and other objects and advantageous features in view, the invention consists of an arrangement of parts more fully disclosed in the detailed description following, in conjunction with the accompanying drawings, and more specifically defined in the claims appended thereto.

Referring to the drawings,

Fig. 1 is an elevation of a furnace equipped with the novel control, parts being broken away;

Fig. 2 is an elevation of the smoker pipe damper 60 control;

Fig. 3 is a side view of the smoker pipe damper section, the swivel parts being shown in section;

Fig. 4 is an enlarged detail view of the check damper;

Figs. 5 and 6 are respectively side and front 5 views of the firebox unit;

Fig. 7 is a vertical section of Fig. 5;

Fig. 8 is a view of the line 8—8 of Fig. 7, parts being broken away;

Fig. 9 is a top plan view of the air preheater 10 unit;

Fig. 10 is a section on the line 10—10 of Fig. 9;

Fig. 11 is a section on the line 11—11 of Fig. 10; and

Fig. 12 is a section on the line 12—12 of Fig. 10. 15

Referring to the drawings, the furnace 15 is equipped with a fire box unit 16 for controlling the admission of air to the combustion space of the fire box and for preheating the admitted air, a damper unit 17 for controlling the outflow of 20 the flue gases, and a device 18 for admitting air below the grate. These units are adapted to be operated in unison by manual movement of a ratchet type control lever 19, which movement is communicated to the units by means of chains or 25 the like 20, 21 and 22; counterweights 23, 24, and 25 are attached to the chains, in the usual manner, to normally hold the units in closed position.

The damper unit is illustrated in Figs. 2 to 4, 30 and includes a casting 26 which is adapted to be mounted in the smoke pipe and is provided with side bosses to which a pivot stud plate 27 and a bearing plate 28 is secured, as by screws or bolts, the damper 29 having a recess 30 to seat over 35 the stud of the plate 27 and having an operating shaft 31 extending through the bearing plate, an operating handle 32 being secured to the end thereof.

The bearing plate 28 is preferably formed with 40 a guide quadrant 33, graduated in degrees, and having stops 34 at each end, whereby movement of the operating handle sets the damper at the desired degree of opening, a stop 35 being provided for the damper to prevent complete 45 closure.

The smoke pipe device or damper unit is further provided with a draft control opening 36 controlled by a slide plate 37 which is slidably mounted on a guide rod 38 seated at its ends 50 in end socket stands 39 secured to suitable bosses of the casting or smoke pipe 26. The plate 37 is shifted by pressing two levers 40 which are pivotally mounted on the plate towards each other, the levers being spring pressed away from 55 each other by a spring 41, and having pins 42 at their inner ends adapted to contact the rod 38 when released.

The operation of the damper unit may now be explained. Movement of the operating handle 60

sets the main damper to the degree of opening, and movement of the slide plate 37 controls the stack draft, and hence the speed of combustion in the fuel bed. The parts are designed for 5 simplicity of operation, are easily assembled, and cannot get out of order under normal operating conditions.

The fire box device is shown in Figs. 5 to 8, and includes an air admission unit 43 and an air 10 preheater unit 44, the two being secured in alignment to the fire box door. The air admission unit includes a base 45 having a central outlet 46 and spaced air flow slots 41, an inlet shell 48 being secured to the base, as by a central screw, 15 and having air admission openings 49; a control valve 50 of plate type is rotatably mounted on the base between the base and the inlet shell, and has slots 51 adapted to uncover the slots 41 in response to movement of the valve 50. The valve 20 50 is shifted by movement of a handle 52, which also functions as a pointer and cooperates with a scale 53 mounted on the base and graduated in degrees; limit stops are provided for the valve, the preferred type including a pin 54 seated in 25 the base and cooperating recesses or notches 55 in the valve 50.

The ash pit air admission unit 18 is in this instance similar in construction to the fire box air admission unit, but is larger. The operation is 30 identical, the valves being rotated manually by movement of the handle, or by securing the operating chain to the handle in any desired and suitable manner, the rotation of the valve uncovering the flow slots to the desired number of 35 degrees as indicated on the scale and regulating the air inflow in accordance.

The air preheater unit is illustrated in detail in Figs. 9 to 12, and comprises a casting 56 which extends into the furnace combustion chamber 40 and through which the air is conveyed in a tortuous manner before emerging from a fan shaped nose provided with many outlets or jets.

The casting has vertical flues or passages 57 through which the hot furnace gases may readily 45 circulate, and has an air inlet 58 which communicates with the upper portion, see Figs. 7 and 11, the air passing between the flues 57 over the central partition 59 to the forward end, and back along the outer sides, then down as shown in Fig. 50 10, and around the flues 57 to the outlets 60 which as shown are drilled to produce sharp edges to ensure maximum velocity of the air passing 55 into the combustion space and are arranged fan shape to distribute the heated air over the entire fire box. The air preheater unit is preferably cast in two parts 61, 62, see Fig. 10, to simplify manufacture.

The operation of the air preheater is as follows: the admitted air is subjected to the fire box heat 60 in its tortuous passage, being initially heated along the upper portion, and then along the lower portion where it is exposed to the direct heat of the fire: the constant passing of the hot gases through the vertical flues or passages facilitates 65 transfer of heat from the hot gases to the air.

It is therefore evident that the novel construction provides an accurate control of the supply of primary air, an accurate control of the supply of secondary air, the secondary air being heated 70 and spread over the coal bed, and an accurate control of the velocity and volume of the outflowing flue gases, whereby the control of combustion is more exact, and the amount of excess air and

the resultant heat loss is reduced to a minimum.

While I have described a specific constructional embodiment of my invention, it is clear that changes in the arrangement, proportions, and relative size of the parts, may be made to suit the requirements for particular installations without departing from the spirit and the scope of the invention as defined in the appended claims.

I claim:

1. An air preheater having a flue extending 10 therethrough, an inlet, a fan shaped nose having a plurality of outlet openings to spread the outflowing air in a wide area, and partitions directing the flowing air in a tortuous passage about said flue to said outlet openings, said passage progressively increasing in area from said inlet to said outlet openings.

2. An air preheater having a plurality of flues extending therethrough, a partition transverse to 20 said flues dividing the interior into an upper and a lower portion, an inlet communicating with the upper portion at one end, a plurality of outlet openings in the lower portion at the other end, and partitions for guiding the air passing into the upper portion between the flues to the other end, 25 back around the flues to the entrance end, and into the lower portion to again pass through and around the flues to the outlet openings.

3. An air preheater having a plurality of flues extending therethrough, a partition transverse to 30 said flues dividing the interior into an upper and a lower portion, an inlet communicating with the upper portion at one end, the other end being formed as a fan shaped nose having a plurality of outlet openings to spread the outflowing air in a 35 wide area, and partitions for guiding the air passing into the upper portion between the flues to the other end, back around the flues to the entrance end, and into the lower portion to again pass through and around the flues to the outlet 40 openings.

4. In combination, an air admission device having a flow control opening, a rotatable valve co-operating with said opening, and an air preheater having a plurality of flues extending therethrough, said air preheater having an inlet communicating with said flow control opening, a partition transverse to said flues dividing the interior into an upper and a lower portion, the inlet 45 communicating with the upper portion at one end, a plurality of outlet openings in the lower portion at the other end, and partitions for guiding the air passing into the upper portion between the flues to the other end, back around the flues to the entrance end, and into the lower portion to again pass through and around the flues 50 to the outlet openings.

5. An air preheater having a flue extending 55 therethrough, an inlet, a plurality of outlet openings, and partitions directing the flowing air in a tortuous passage about said flue to said outlet openings, the cross sectional area of said tortuous passage progressively increasing towards the outlet openings.

6. An air preheater having two flues extending 60 therethrough, an inlet, a plurality of outlet openings, and partition means guiding the flow of air between the flues forwardly from said inlet, then 65 backwardly around the flues, then forwardly between and around the flues to said outlet openings.

ALBERT W. HOLMES.
